TABLECLOTH

Lula Jane Pyle and Maxine H. Schell,
Kansas City, Mo.

Application March 8, 1948, Serial No. 144,976

Term of patent 3½ years

(Cl. D92—26)

To all whom it may concern:

Be it known that we, Lula Jane Pyle and Maxine H. Schell, citizens of the United States, residents of Kansas City, in the county of Jackson and State of Missouri, have invented a new, original, and ornamental Design for a Table-cloth, of which the following is a specification, reference being had to the accompanying drawing, forming a part thereof.

The figure in the drawing illustrates a top plan view of a tablecloth, showing our new design, the back thereof being plain and without ornamentation.

We claim:

The ornamental design for a tablecloth, as shown and described.

LULA JANE PYLE.
MAXINE H. SCHELL.
